[57] CLAIM

The ornamental design for a remote locator, as shown and described.

DESCRIPTION

FIG. 1 is a front view of a remote locator showing a first embodiment of my new design;

FIG. 2 is a left side view thereof, with the right side being a mirror image;

FIG. 3 is a bottom plan view thereof;

FIG. 4 is a top plan view thereof;

FIG. 5 is a rear view thereof;

FIG. 6 is a front view of a remote locator showing a second embodiment of my new design;

FIG. 7 is a rear view thereof;

FIG. 8 is a front view of a remote locator showing a third embodiment of my new design;

FIG. 9 is a front view of a remote locator showing a third embodiment of my new design; and,

FIG. 10 is a top plan view thereof.
